DESIGN FOR A PIANO

George W. Cushing, Newark, N. J., assignor to
Krakauer Bros., New York, N. Y., a corpora-
tion of New York

Application March 4, 1942, Serial No. 106,071

Term of patent 7 years

To all whom it may concern:

Be it known that I, George W. Cushing, a citizen of the United States, residing at Newark, Essex County, State of New Jersey, have invented a new, original and ornamental Design for a Piano, of which the following is a specification, reference being had to the accompanying drawings, forming a part thereof.

Figure 1 is a front perspective view of a piano, showing my new design;

Figure 2 is a rear perspective view;
Figure 3 is a top plan view;
Figure 4 is a bottom plan view; and
Figure 5 is an end elevation thereof.
I claim:
The ornamental design for a piano, as shown.

GEORGE W. CUSHING.
